UNITED STATES PATENT OFFICE.

CHARLES RUTSON, OF JACKSON, MICHIGAN, ASSIGNOR TO JACKSON CUSHION SPRING COMPANY, OF JACKSON, MICHIGAN.

SPRING CONSTRUCTION.

No. 914,312.

Specification of Letters Patent.

Patented March 2, 1909.

Application filed September 3, 1908. Serial No. 451,578.

To all whom it may concern:

Be it known that I, CHARLES RUTSON, a citizen of the United States, residing at Jackson, in the county of Jackson and State of Michigan, have invented certain new and useful Improvements in Spring Constructions, of which the following is a specification.

This invention relates to spring constructions.

One object is to provide a spring construction for automobile or other seats embodying such characteristics that the rider of the structure will not be injured or inconvenienced by reason of contact with the support upon which the structure is mounted in the event that the seat should be jarred incident to the weight of a heavy rider or in the event of the vehicle contacting with an obstruction in the roadway.

Another object is to reinforce the main springs of the structure with one or more single or compound auxiliary springs adapted to be compressed when the structure is subjected to unusual weight, whereby the auxiliary springs will catch the extra weight and prevent the structure from being wholly compressed.

With the above and other objects in view, the present invention consists in the combination and arrangement of parts hereinafter more fully described, illustrated in the accompanying drawings, and particularly pointed out in the appended claims, it being understood that changes may be made in the form, proportion, size and minor details without departing from the spirit or sacrificing any of the advantages of the invention.

In the drawings:—Figure 1 is a plan view of the invention. Fig. 2 is a transverse sectional view. Fig. 3 is a detail perspective view of one of the auxiliary reinforcing elements. Fig. 4 is a fragmentary sectional view through the structure illustrating one end of one of the arch springs mounted upon its supporting means.

Referring now more particularly to the accompanying drawings, the reference characters 1 and 2 indicate upper and lower edge wires, which may be rectangular in formation or which may have one end curved, as indicated at 3.

If the cushion is formed round at one end, as shown, there will be a curved supporting

wire 4 adapted to coöperate with the curved lower edge wire 2 for the support of the forward main springs 5.

Coöperating with the rear end of the structure is a supporting wire 6 upon which and the rear end of the lower edge wire are mounted the rear main springs 5, there being pairs of supporting wires 7 arranged between the aforesaid supporting wires 4 and 6 for the support of other main springs 5. These supporting wires may be disposed within the frame formed by the upper and lower edge wires in any suitable manner and the springs may be secured in place at their lower ends by means of suitable clips 9 and 11 at their upper and lower ends along the border or upper edge wire by means of suitable clips 11. The clips employed in connection with the springs are not claimed in this case, and it will be understood that they may be of any particular variety.

Between certain of the main spring supporting wires are arranged auxiliary supporting elements α including spaced parallel members 10, and these auxiliary supports 80 may be secured to opposite sides of the lower edge wire by means of suitable clips 11.

Slidably mounted upon each auxiliary support α is a series of short flat spring metal elements forming arch springs 12, each arch spring 12 of each series having its opposite ends directed downwardly, as indicated at 13 and provided with a pair of perforations 14 adapted to embrace the parallel members 12 of the respective auxiliary support 90 wires, whereby the arch springs may slide independently or together upon the auxiliary support wires when the structure is subjected to heavy weight.

It will be seen that the arch springs have 95 their intermediate or highest points terminating short of the upper convolutions of the main springs so that if the main springs are subjected to a light pressure, the auxiliary arch springs will not be compressed 100 at all, but only when the main springs are practically completely compressed, thereby preventing the heavy weight of the rider from passing below the lower edge wire. When these auxiliary arch springs are compressed 105 their ends slide upon the auxiliary support wires and their bodies move toward and sometimes rest upon the auxiliary support wires.

If desired, I may secure the lower ends of 110

a second set of auxiliary springs 15 to the backs of the auxiliary arch springs by means of a suitable fastening 16. This second set of auxiliary springs 15, as shown, are of the cone variety with their apexes secured to the arch springs, but if desired, the position of the second set of auxiliary springs may obviously be reversed. In any event, the tops of the second set of auxiliary springs 10 terminate below the upper convolutions of the main springs, so that the double set of auxiliary springs may catch the extra weights for the purposes stated. At any rate, when the auxiliary set of springs 15 are 15 compressed, it follows that the other set of auxiliary springs 12 are compressed, but neither set of auxiliary springs are compressed until the main springs have been subjected to unusual weight.

20 From the foregoing, it will be understood that the second set of auxiliary springs may be dispensed with, and I also wish it understood in practice that the arch auxiliary springs may slide into abutting relation as 25 regards the arch springs of each series when compressed, or be separated from one another at such time or when not compressed. What is claimed is:—

1. A spring construction comprising a frame, main springs mounted within the frame, one set of auxiliary springs mounted between the main springs, and another set of auxiliary springs connected to the first mentioned auxiliary springs for coöperation with the latter to catch the extra weight.
2. A spring construction comprising a frame, main springs mounted within the frame, a set of auxiliary arch springs mounted within the frame between the main 40 springs, and another set of auxiliary springs connected to said arch springs for coöperation with the latter to catch the extra weight.
3. A spring construction comprising a frame, main springs mounted within the frame, and a set of longitudinally alining auxiliary springs slidably mounted at each end within the frame between the main springs.
4. A spring construction comprising a frame, main springs mounted within the frame, a set of auxiliary springs slidably mounted within the frame between the main springs, and another set of auxiliary springs connected to the first mentioned auxiliary 55 springs for coöperation with the latter to catch the extra weights.
5. A spring construction comprising a frame, main springs mounted within the frame, and longitudinally alining auxiliary arch springs slidably mounted at each end within the frame.
6. A spring construction comprising a frame, main springs mounted within the frame, auxiliary arch springs slidably mounted within the frame, and another set 65

of springs connected to the arch springs and disposed above the latter to coöperate therewith to catch the extra weight.

7. A spring construction comprising a frame, main springs mounted within the frame, and separate series of spaced longitudinally substantially semi-elliptical alining arch springs mounted within the frame to catch the extra weight.

8. In a spring construction, a frame, main springs mounted in the frame, and a plurality of spaced substantially semi-elliptical alining arch springs mounted within the frame to catch the extra weight.

9. A spring construction comprising a frame, main springs mounted within the frame, separate series of alining arch springs mounted within the frame to catch the extra weight, and other springs connected to the tops of the arch springs.

10. A spring construction comprising a frame, main spring supporting wires mounted in the frame, main springs secured to said supporting wires, auxiliary spring supporting wires mounted in the frame and each including a pair of spaced members, and longitudinally alining auxiliary arch springs each having their ends provided with perforations to embrace the auxiliary spring supporting wires whereby they may slide upon the latter upon compression.

11. A spring construction comprising a frame, main spring supporting wires mounted in the frame, main springs secured to said supporting wires, auxiliary spring supporting wires mounted in the frame and each including a pair of spaced members, auxiliary arch springs each having their ends provided with perforations to embrace the auxiliary spring supporting wires whereby they may slide upon the latter upon compression, and other auxiliary springs connected to the tops of each of the aforesaid arch auxiliary springs.

12. In a spring construction, a frame, main springs in the frame, a series of alining arch springs mounted within the frame, and a spring connected to each arch spring intermediate the ends of the latter for coöperation therewith to catch the extra weight.

13. In a spring construction, a frame, main springs in the frame, a series of alining arch springs in the frame, a spring connected to the top of each arch spring for coöperation with the latter to catch the extra weights, the third mentioned springs being disposed vertically and terminating at their upper ends short of the upper ends of the main springs.

14. In a spring construction, a frame, main springs in the frame, and a series of spaced substantially semi-elliptical alining arch springs mounted within the frame to catch the extra weight, the highest point of

each arch spring being below the plane of the highest convolutions of the main springs.

15. In a spring construction, a frame, main springs in the frame, a series of alining arch springs mounted within the frame to catch the extra weight, the highest point of each arch spring being below the plane of the highest convolutions of the main springs, and a spring secured to each arch spring for coöperation therewith.

16. In a spring construction, a frame, main springs in the frame, a series of alining arch springs mounted within the frame to catch the extra weight, the highest point of each arch spring being below the plane of the highest convolutions of the main springs, and a coiled spring secured to the top of each arch spring for coöperation therewith.

17. In a spring construction, a frame, main springs in the frame, a series of auxiliary arch springs in the frame to catch the extra weight, and a spring disposed on top of each arch spring for coöperation therewith.

18. In a spring construction, a frame, main springs in the frame, an arch spring coöperating with the main springs to catch the extra weight, said arch spring being

slidably mounted at each end within the frame, and a coiled spring mounted on top of the auxiliary arch spring.

19. In a spring construction, a frame, main springs in the frame, an auxiliary arch spring in the frame for coöperation with the main springs, and another auxiliary spring mounted upon top of said arch spring and at its upper end terminating short of the upper ends of the main springs.

20. In a spring construction, a frame, main springs in the frame, and a plurality of longitudinally alining substantially semi-elliptical shaped arch springs in the frame to catch the extra weight.

21. In a spring construction, a frame, main springs in the frame, and a plurality of longitudinally alining substantially semi-elliptical shaped arch springs in the frame to catch the extra weight, each arch spring being slidably mounted at each end within the frame.

In testimony whereof I affix my signature, in presence of two witnesses.

CHARLES RUTSON.
